Fig. 5.

Fig. 6.

A technical drawing of a double-acting cylinder assembly. The drawing shows a central vertical cylinder body with two horizontal ports on the left and two on the right. Each port is connected to a rod, which is secured to a base plate. The base plate features a central slot and two side slots. The entire assembly is mounted on a rectangular base. Various dimensions are indicated: 34 for the total height of the cylinder body, 12 for the height of the base plate, and 30 for the width of the base plate. The drawing uses hatching to distinguish different parts of the cylinder body.

JULIUS MINTZ, OF NEW YORK, N. Y.

TICKET-ASSEMBLING APPARATUS.

1,309,044.

Specification of Letters Patent.

Patented July 8, 1919.

Application filed April 20, 1917. Serial No. 163,469.

To all whom it may concern:

Be it known that I, JULIUS MINTZ, a citizen of the United States of America, residing at 911 Longwood avenue, Bronx, in the 5 county of Bronx and State of New York, have invented new and useful Improvements in Ticket-Assembling Apparatus, of which the following is a specification.

This invention relates to deposit and collection receptacles, and more especially to 10 those intended for punching and canceling tickets and the like; and the objects of the same are to produce an apparatus which will automatically extract a series of tickets, 15 coupons, or the like, from a card receptacle having pockets into which they have been slipped, and assemble or bunch the tickets so that they may be more readily handled; and also to provide the apparatus 20 with means for perforating or canceling the tickets in the act of withdrawing them from the card and assembling them.

A custom has grown up for paying piece-work employees by cashing tickets turned in 25 by them, each ticket having been awarded in consideration of a piece of work done. These tickets, sometimes in coupon form, are given to the workman with the piece of work, and a card receptacle has been devised and patented having pockets into 30 which he inserts the tickets as the finished work is turned in. This receptacle has pages or stiff leaves, each provided with pockets in five rows of five each, or twenty-five pockets to the page; and piece-work prices are 35 paid at so much per page. For instance, if a piece of work be worth two cents, the employee is given a yellow ticket or coupon with each piece, and when he finishes the 40 work and turns it in he sticks the ticket into one of the pockets of the receptacle. When all of the twenty-five pockets have been filled, he may turn in the page or card and the cashier multiplying the number of pockets by the value of the tickets pays the workman fifty cents and retains the tickets as his 45 voucher.

The purpose of the present invention is to produce a machine whereby the twenty-five tickets in the example may be mechanically withdrawn from the pockets and assembled or bunched so that the cashier may put the bunch of tickets in a receptacle such as an envelop or may tie them up into a 50 bundle—in either case having a voucher for the payment he has made. Lest the tickets

might be used a second time, a feature of my invention is the provision of means for canceling the tickets as they are withdrawn from the card-pockets, and of course canceled tickets may not be used a second time. 60

With this general explanation of the conditions leading up to the desirability of a device of this kind, I proceed to a description of its construction and operation, reference being had to the accompanying drawings wherein:—

Figure 1 is a front elevation, partly in section, showing this apparatus ready for use.

Fig. 2 is a left end elevation, its upper portion in section on the line 2—2 of Fig. 1.

Fig. 3 is an enlarged sectional detail of one of the punchers.

Fig. 4 is a slight modification.

Fig. 5 is a side elevation, and Figs. 6 and 7 are sections on the lines 6—6 and 7—7 thereof, showing an amplification of the idea; and Fig. 8 is a detail illustrating the strippers.

The receptacle referred to above is a card designated in Fig. 1 by the letter 'C' and having five rows of five pockets each designated by the letter 'P', and into these pockets are stuck the lower ends of coupons or tickets 85 T whose lower portions L are held by the pockets closely against the face of the card and whose upper portions rise out of the pockets of one row and overlap the pockets of the row above slightly—all as will be 90 clear from Fig. 1 if we remember that we have a section of the card receptacle laid on its back and are looking at an upright row of the tickets T therein.

In the drawings the numeral 1 designates 95 a rectangular casing or frame whose open upper end may be flanged or rabbeted as at 2 to permit the edges of the card 'C' to rest thereon, excepting that I would omit the rabbet from the front wall 3 as seen in Fig. 100 2. This frame is a little longer than the length of the card as seen in Fig. 1 and is a little narrower than the width of the card as seen in Fig. 2, and therefore when the card is laid on its back with its edge on 105 the rear rabbet and its upper end on the lefthand rabbet, its front edge overlaps the front wall as seen in Fig. 2 and its lower edge does not reach completely to the right hand rabbet as seen in Fig. 1. All this has 110 a purpose as will be explained. The bottom of the casing connects with a hopper 4 whose

walls converge downward to a chute or mouth 5 capable of being closed or opened by a slide or valve 6, and below the latter the front or possibly one side of the chute 5 is cut away as at 7 so that the operator may put his hand into the same for packing accumulated tickets down into the mouth of a bag or other receptacle R as indicated in Fig. 1. This receptacle may rest on a base 8 such as a table top, and from the base suitable supports 9 may rise to the hopper so that the chute 5 will stand elevated from the base a sufficient distance to permit the insertion and removal of the receptacle whatever the character of the latter.

Secured at 13 to the rear wall of the casing is a comb-like structure whose teeth or fingers 12 (here shown as five in number) lead forward over the open upper end of the casing and are preferably sharpened at their front ends as at 11, the fingers being disposed in strict parallelism and spaced to correspond with the spacing of the tickets T when mounted in the pockets P of a card C. The front ends 11 of the fingers may overlie the front wall 3 as indicated in Fig. 2, but normally they stand a little above and out of contact with the same so that the card C may be slipped over this wall and under the fingers. Disposed wholly above the comb is a plate 14 which may be entirely solid or might have slots or openings 15 as indicated in Fig. 1 but which are necessarily at other points than directly above the fingers, and from each end of this plate depends a plunger 16 passing downward through upright tubular guides 17 disposed in pairs on the ends of the casing. Between the guides of each pair the plunger has a pin 18 supported by a coiled expansive spring 19 which rests on the lower guide and holds the pin normally in contact with the upper guide and therefore holds the entire plate normally elevated as shown. This means for holding the plate normally raised is illustrative only, and other means might be employed. The lower ends of the plungers are pivotally connected in any suitable manner at the point 20 with levers 21 fulcrumed as at 22 in supports or brackets 23 on the casing and leading thence forward past the pivots 20 to the front of the apparatus. Here they may have individual handles 24, or they may be connected by a cross bar 25 having its own handle 26, or, in fact, both handles may be employed. This detailed construction of the operating mechanism is also illustrative, and might be replaced by another; but the idea obviously is that when the cross bar or any handle is depressed, the plungers are moved downward through their guides and the entire plate is depressed for a purpose yet to appear, whereas at other times the springs hold the plate elevated or inactive.

For canceling the tickets and mutilating or punching them, the plate 14 carries a series of pins 30 which in the illustration will be disposed in five rows and with five in each row, the rows spaced to correspond with the spacing of the fingers and checked in the opposite direction to correspond with the spacing of the pockets P in the card C. As seen in Fig. 3, each pin has at its lower end an enlarged head 31 whose lower face 75 is pointed as at 32, and directly beneath the point the finger 12 has a socket 33 in the illustration given. It is quite conceivable that the point could be of other shape and the socket continued into an opening, and it 80 is even possible that these might be the male and female elements of a die so that when the head was projected completely through a hole instead of a socket, the ticket would be punched. However, the idea is that in 85 some manner the ticket will be canceled as by mutilation, punching, printing or otherwise indenting it at this point. As it is possible that the pin may pick up the ticket in the upward movement after it has been mutilated, I provide a stripper as best seen in Figs. 1 and 3. This is composed of a series of strips 34, each overlying and paralleling one of the fingers 12, and each strip has 90 through it five holes 35 loosely embracing the five pins 30, the holes being counter-bored or enlarged at their lower ends at 36 to produce sockets of sufficient size to loosely receive the heads 31 and to wholly inclose their points when the stripper stands in normal position as seen in Fig. 3. It is obvious 95 now that when the point is brought down onto the ticket and embedded therein, the stripper will rise slightly, and when the pin is again elevated so that its tip rises out 100 of the socket 33 the stripper will push the ticket off the point in case it has become stuck thereon. For assisting it in this action I may provide springs 37 around the pins 105 between the plate 14 and the stripper 34. 110

The operation of this device will be as follows: The workman accumulates his tickets in the pockets P of a card C until they are all filled, and it may be well to establish a rule that all tickets of one valuation (probably of one color) must be placed in the pockets of one card. At an appointed time all workmen bring these cards to the cashier and the latter, instead of removing the tickets by hand and counting them one 115 by one, employs this apparatus for mechanically removing the tickets from a card, canceling them, and assembling or bunching them as first suggested above. Placing the rear edge of a card on the front wall 3 of 120 the casing and with its upper end in the left hand rabbet 2 as seen in Fig. 1, he pushes the card slowly backward with the result that the sharpened front ends 11 of all the 125 fingers 12 pass under the free ends of the 130

several rows of tickets T and raise them slightly from the card until the parts assume the position shown in Fig. 1. The lower ends L of all tickets still rest in the 5 pockets P of the card, and the far edge of the latter at last comes to rest in the rear rabbet 2 of the casing 1 as seen in Fig. 2 with its front edge projecting slightly over the front wall 3 and possibly held in the 10 hand of the operator. Now he depresses the cross-bar 25 or one of the handles thereon, and the plungers 16 cause the downward movement of the top plate 14 and all the punches. The points 32 of the latter strike 15 upon the projecting upper ends of the tickets and indent them into the sockets 33, or possibly they are pushed completely through the fingers 12 if holes instead of sockets are used; in any event each ticket 20 is mutilated and thereby canceled by this movement, and meanwhile the stripper rises slightly. It is possible, and in fact it is quite probable, that this depression of the canceling mechanism will depress the front 25 ends of the fingers slightly, but if they overlie the front wall 3 they will be supported thereby. The operator now moves the card to the right as seen in Fig. 1, possibly letting up a little on the pressure on the cross- 30 bar and therefore permitting the spring fingers to rise slightly out of engaging contact with the cards and such movement of the latter withdraws the pockets P from the lower ends of the several tickets while the 35 tickets are meanwhile held at their upper ends where they are clamped between the points 32 and the sockets 33. The operator now draws the card C slowly toward him while its lower end rests in the right hand 40 rabbet in Fig. 1, with the result that the card is drawn entirely out of the apparatus and the tickets are left therein, each being clamped between a finger and the superimposed stripper and held against rotation by 45 the spring 37 bearing the stripper downward. It is also held against rotation by the indentation made into the ticket by the cancellation point 32 and the socket 33. When the card is entirely out of the 50 apparatus, each ticket at its lower end which formerly rested within a pocket P will underlie the finger next adjacent that upon which it is clamped, excepting that the right hand ticket in Fig. 1 will be clamped at its 55 left end and its right end will be entirely free. Thereafter when pressure on the cross bar is relieved and the plate and stripper rise to their inactive positions, all tickets 60 will drop by gravity through the slots between the fingers, through the casing 1, down through the hopper 4, and be collected or assembled within the chute 5 wherein they remain until the slide valve 6 is withdrawn, when they fall into the receptacle R. 65 The latter may be used or not, and if not

the operator may put his hand under the lower end of the chute and gather the bunch of tickets, all of which are canceled, and may count them and tie a string or place a rubber around them.

Attention is now invited to Fig. 4 wherein I have shown a slightly different form of point 32 and socket 33 from that illustrated in Fig. 3. Herein the canceler has a plurality of points 310 and the female member 70 of the die is formed to correspond as indicated at 320, and it is quite conceivable that these points could be very fine so as to be almost in the shape of needles, and that they could be arranged to perforate the tickets 75 with a little word or abbreviation such as "Pd." In any event, if the canceler is other than a cone as shown at 32 in Fig. 1 and the female die is shaped to correspond, there will be no possibility that the ticket will 80 rotate on this canceler as the card is withdrawn from the apparatus. Such rotation is resisted also by the stripper, but it may be that the stripper can be omitted if it is found to be superfluous. I reserve the privilege of making this change or others which 85 come within the scope of the appended claims. The essential idea is that the canceling or mutilating mechanism shall be such that it will both reliably cancel the ticket 90 and hold it while the card is being withdrawn transversely. Any kind of a mutilating point will hold the ticket while the card is being withdrawn longitudinally, so that the lower end L of the ticket pulls out 95 of the pocket, but after the card is entirely removed it is essential that a considerable portion of the ticket shall stand in the space between two fingers and underlie the next adjacent finger, so that when the plate and 100 strippers are raised the tickets will drop by gravity as described above.

In some constructions of the card receptacle C, there are pockets P on both faces of each card; but it is quite clear that if 105 the card shown in Fig. 1 had another series of pockets and another set of tickets on its under side, these would not be affected by the operation of withdrawing the tickets from its upper side. After this has been 110 accomplished the card could be reversed and inserted a second time and the second group of tickets would be canceled and withdrawn like the first, although of course it would be necessary that the pockets be disposed in 115 like rows and in identical spacing in both rows so that the canceling pins or punches and the several fingers would operate successfully, whichever side up the card was placed. I have spoken throughout this 120 specification and will speak in the claims of "tickets", but it is clear that these might be coupons and as such they might be of paper stock rather than card: however the apparatus is capable of operating on ele- 125 130

ments T which are of paper and not so stiff as cards, as their stiffness is not essential to its success. In busy factories where it is not always desirable to reverse the card 5 and insert it a second time to withdraw a second group of tickets, I may employ that type of my structure illustrated on Sheet 3 of the drawings, and wherein the tickets on both sides of the card are simultaneously 10 canceled and simultaneously withdrawn by one action. When this type of machine is employed, if a card should be presented which has only one group of tickets, the punches at one side of the machine will act 15 on that group while of course the punches at the other side do nothing; and therefore what might be called the double type of my machine is capable of operating on either a single or a double card, whereas the single 20 type of the machine can operate only on a single card. In many respects this double type of the machine follows closely the construction of the one described above, but in one essential it is quite different. Details 25 will be set forth below.

Mounted on supports 9 is a casing 1' having at its lower end a hopper 4 whose walls converge toward a mouth or chute 5, and in plan view this casing is U-shaped as seen 30 in Fig. 7, one wall being closed at the edge of the casing as at 2' and the other edge being open as at 7'. The card C shown herein has two sets of pockets P and tickets T are inserted in these pockets as described 35 above, differing only in that there are two sets or groups of tickets, one on each side of the card. The essential feature of difference between this type of my invention and that already described is that the plates 14 40 above are replaced in the present case by the side walls of the casing which I call plates 14'; and, while the fingers above were stationary and the plates moved toward them, the plates in the present instance are 45 stationary and the fingers move. There are here duplicate comb-like structures whereof each comprises a back 13' and five fingers 12 having reduced tips 11, and cavities 36' are formed in the outer faces of the fingers; 50 and the canceling pins or points 30' are carried by the plates 14' as best seen in Fig. 6. To the back of the comb is connected a pair of plungers 16' passing through holes 17' in the side walls or plates 55 14' of the casing and having transverse pins 18' through their outer ends. Levers 21' rise from a rock shaft 25' and have slots 20' in their outer bifurcated ends loosely engaging said pins 18'. The rock shaft has a lever 60 24' connected by links or other elements 23' with a treadle mechanism 26' in the present case which takes the place of the main handle 26. The actuating mechanism for moving the combs is only illustrative, and I 65 serve the right to use other means if thought

advisable. In Fig. 8 is shown how strippers 34 might be employed, inclosing the pins 30 and advanced by springs 37 precisely as above described and therefore needing no 70 ampler description.

The operation of this type of my device will be as follows: When a double card with its fifty tickets is brought to the cashier, he turns it with one edge upward and passes the other edge downward into the 75 open upper end of the casing 1' while the upper end of the card is held close against the closed end 2' of the casing as seen at the top of Fig. 5. This causes the free ends of all the tickets T to pass over the tips 11 80 of the two sets of fingers 12, while the card C moves down between their bodies as seen in Fig. 6. Now he depresses the treadle 26 (or actuates the other operating mechanism, whatever its type), with the result 85 that the rock shafts 25' move in unison in their bearings 22' and the several levers 21' draw outward on the plungers 16' against the tension of their springs 19', so that the backs 13' of the combs and all of the fingers 90 thereof are moved outward or away from the interposed card. The result is that the fingers press the tickets onto the perforating or punching points 30' and mutilate or cancel them. Now, yet holding the actuating mechanism under some tension, he draws the card laterally out of the casing by moving it to the right as seen in Fig. 5, with the result that all the tickets are 95 drawn from the pockets P as above; and then 100 when the actuating mechanism is released, the tickets are free to fall through the hopper 4 and mouth 5 and into a suitable receptacle if one be provided. Without further description it is obvious that if the 105 strippers 34 are employed as seen in Fig. 8, there is no danger that any of the tickets will be caught on the pins or points 30' and hang there undesirably. It is also 110 obvious that special forms of punching 115 points might be used as shown in Fig. 4, and in this case possibly one set of points could be employed on one side plate 14' and another set or another type on the other plate so that the card might contain a series 120 of one kind of tickets T on one face and another series of another kind on the opposite face: however, these are details which may benefit the user.

What is claimed as new is:—

1. An apparatus of the class described comprising an open topped casing, a plurality of fingers projecting across the open top thereof, a movable element overlying said fingers and standing normally above them, and means for depressing said element.
2. An apparatus of the class described comprising a receptacle, a slideway within said receptacle adapted to receive and hold a ticket card, fingers arranged in proximity 130

- to said slideway and disposed to pass between the card and tickets carried thereby and stripping means adapted to coöperate with said fingers to strip off said tickets.
- 5 3. An apparatus of the class described comprising a container, a slideway at the open end of said container adapted to receive a ticket holding card, fingers extending across the top of said container and adapted to pass between the tickets and the card a plate disposed normally above said fingers, penetrating members carried by said plate and coöoperating with said fingers for mutilating a ticket disposed therebetween and means for depressing said plate.
- 10 4. A device of the character described comprising an open topped receptacle, a slideway at the open top thereof and adapted to support a ticket holding card, a plurality of fingers extending across said top and adapted to pass between the card and the tickets held thereby, stripper members extending above said fingers, a plate disposed above said stripper members, penetrating members carried by said plate and operable through said stripper members to coöperate with said fingers for mutilating a ticket between the fingers and the stripper members, and means for moving said plate.
- 15 5. An apparatus of the class described comprising an open topped receptacle, a comb-like structure secured to the rear wall thereof and having fingers projecting forwardly across its open top, a slideway in said open top adapted to support a ticket holding card, a plate extending across said fingers springs holding said plate normally elevated, penetrating members depending from said plate and coöoperating with said fingers, and stripper members having movement relative to said plate and receiving said penetrating members.
- 20 6. In an apparatus of the class described, the combination with a box-like casing, a comb-like structure carried by its rear wall and having fingers projecting forwardly across its open mouth, a top plate normally elevated above said comb-fingers, and manually operable means for bringing it down onto them and raising it when desired; of a hopper connected with the bottom of said casing and whose side walls converge to a chute at its lower end, and means for delivering articles through the chute when desired.
- 25 7. An apparatus of the class described comprising a casing having an open portion, a plurality of fingers projecting across said open portion, a movable element disposed in proximity to said fingers, mutilating members carried by said movable element, and means for moving said element.
- 30 8. An apparatus of the class described comprising a receptacle, a slideway within said receptacle adapted to receive and hold
- a ticket card, fingers arranged in proximity to said slideway and disposed to pass between the card and tickets carried thereby, and perforating means adapted to coöperate with said fingers for mutilating said tickets.
- 35 9. An apparatus of the class described comprising a receptacle, a slideway within said receptacle adapted to receive and hold a ticket card, fingers arranged in proximity to said slideway and disposed to pass between the card and tickets carried thereby, stripping means adapted to coöperate with said fingers to strip off said tickets, and means associated with said stripping means for mutilating said tickets.
- 40 10. An apparatus of the class described, comprising a receptacle, a slideway within said receptacle adapted to receive and hold a ticket card, fingers arranged in proximity to said slideway and disposed to pass between the card and tickets carried thereby, a bar disposed normally spaced from said fingers, penetrating members carried by said bar and coöperating with said fingers for mutilating a ticket disposed therebetween, and means for depressing said bar.
- 45 11. An apparatus of the class described comprising a casing having an open portion, a plurality of fingers projecting across said casing, a movable element adjacent said fingers, and means for moving said element toward and from said fingers.
- 50 12. An apparatus of the class described comprising a casing, a support, a plurality of fingers projecting across said casing adjacent said support, a movable element adjacent said fingers and movable into engagement therewith.
- 55 13. An apparatus of the class described comprising a casing, a support adapted to receive and hold a ticket holding card, and means within said receptacle movable into penetrating engagement with tickets disposed on said card.
- 60 14. An apparatus of the class described comprising a receptacle, a support within said receptacle adapted to receive and hold a ticket holding card, penetrating members movable into engagement with tickets on said card, and means for stripping the tickets from said penetrating members.
- 65 15. An apparatus of the class described comprising a casing, a support within said casing adapted to receive a ticket holding card, and automatically coöoperating mutilating and stripping means movable to engage tickets on said card and each other respectively.
- 70 16. An apparatus of the class described comprising a casing adapted to receive a ticket holding card, and means movable for mutilating tickets held by said card and stripping said tickets from the card.
- 75 17. An apparatus of the class described comprising a casing adapted to receive a

- ticket holding card, and means movable into engagement with the tickets held by the card whereby the tickets may be stripped 15 from the card, and a receptacle associated with said casing below said support whereby said tickets may be collected.
5. 18. An apparatus of the class described comprising a casing adapted to receive a ticket holding card, means for stripping the tickets from the card and means for collecting said tickets.
10. 19. An apparatus of the class described comprising a casing, a support associated with said casing and adapted to receive a ticket holding card, members movable into
20. An apparatus of the class described comprising a support adapted to receive a ticket holding card, means for mutilating tickets held by said card, means for stripping said tickets from said card and means for collecting said tickets.

In testimony whereof I affix my signature. 25
JULIUS MINTZ.
